UNITED STATES PATENT OFFICE

ARMIN L. SCHREIBER, OF SANTA MONICA, CALIFORNIA, ASSIGNOR TO AMERICAN EN-
CAUSTIC TILING COMPANY, LTD., OF NEW YORK, N. Y., A CORPORATION OF NEW
YORK

TILE SETTER

Application filed August 12, 1929. Serial No. 385,367.

This invention relates to improvements in tile setters or means for exposing ceramic ware to the heat of a kiln during heat treatment, and while it is primarily used in connection with the firing of wall and floor tile, it is to be understood that it is available for the heat treatment of ceramic products generally. This relates to devices of the kind shown in Prouty Patent No. 1,676,799 and 5 in the co-pending application filed by William McCoy, Serial No. 290,231 which has become Patent 1,778,561.

An object of this invention is to provide a separable device of this character which will 15 support a plurality of ceramic products in spaced relation in a kiln during the heat treatment whereby all surfaces of the products are subject to heat.

Further objects of the invention include 20 improvements in details of construction and arrangement whereby different forms of ceramic products may be properly supported during heat treatment, and whereby the setter may be readily assembled and knocked down. 25 The device is simple and easy to make and efficient in supporting a large number of ceramic products during treatment.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure, several embodiments of my invention, it being expressly understood, however, that various 30 changes may be made in practice within the scope of the claims without disengaging from my inventive idea.

In the drawings—

Figure 1 represents a perspective view of 45 one embodiment of my invention, assembled.

Figure 2 is a view similar to Figure 1 in which the supporting shoulders are of slightly different formation.

Figure 3 is a detailed elevation of the supporting element shown in Figure 1.

Figure 4 is a detailed elevation of the supporting element shown in Figure 2.

Figure 5 is a detail of the construction shown in Figure 1, illustrating the method of assembling.

Figure 6 is a perspective view of a slightly modified form of my invention.

Figure 7 is a detail view of the lower portion of the construction shown in Figure 6.

A tile setter constructed according to my 60 invention embodies essentially a top plate 1, a bottom plate 2 and a plurality of corner posts 3. In the form shown the top and bottom plates are rectangular in shape and, therefore, the corner posts are four in number. As shown in Figure 5, the top and bottom plates are provided with the enlarged or reinforced corner portions 4 which are provided with the sockets 5 adapted to receive the reduced end or tenon 6 on the top 70 and bottom ends of the corner posts 3. The fit between socket 5 and tenon 6 is loose, the reduced ends being slightly smaller than the sockets and, therefore, resting on the bottom parts 7 left in the sockets. At the same time the shoulders 6' rest upon the top surface of the enlarged corners 4 about the socket, whereby the posts are free to move slightly when in the sockets to allow the setter to adjust itself to the expansion and contraction 80 encountered in the heating and cooling of the setter. In order to lighten the structure the corner posts are hollowed out on their rear faces as at 3". Not only are the top and bottom plates provided with the enlarged corners 4 to space these plates from the bottom of the kiln, but they are also provided with the upraised ribs 8 which space the tile supported thereby from the bottom of the setter. 85

The corner posts are provided with a plurality of lugs or shoulders upon which the edges of the tiles or other ceramic products, or the supporting means therefor, rest during heat treatment. In the form shown in Figures 1 and 3 these lugs or shoulders are designated by the numeral 9, being in the form of a sharply angled member joined to the vertical face 10 of the corner post by the slightly inclined face 11. When the setter is assembled the corner posts are arranged so that 90 95 100

these lugs or shoulders are opposed to each other so as to form opposed parallel supports for the tiles. Therefore, the space between these lugs or shoulders is equal to the thickness of the tile plus the clearance between the tiles necessary to leave sufficient space for proper heat treatment. In Figure 1 are shown two forms of ceramic products, 12 designating cap tiles, and in which 13 designates a supporting plate supported by the lugs or shoulders forming tables or supports for the smaller tiles 14.

In the form shown in Figures 2 and 4 the lugs or shoulders 15 are similar to those previously described, but they are arranged closely together and separated only by the width of the inclined surface 16. This form of structure is adapted to support bullnose tiles 17 which are preferably inserted in alternation in the setter.

In the form shown in Figures 6 and 7 the construction as a whole is similar except that the top and bottom plates 1' and 2' are provided with inclined sockets 5' in the enlarged corner portions 4', which receive inclined or beveled tenon 6' of the corner post 3'. These sockets 5' open entirely through the bottom and top plates 1' and 2'. The lugs or shoulders 9' are substantially the same and are suitably spaced apart by the inclined surfaces 11' to provide the necessary space between the tiles being treated.

The parts of this device are preferably composed of a biscuit mixture pressed to the required form and of accurate dimensions and fired in a kiln to approximate maturing temperature. It is to be noted that in each instance there is an inclined surface provided on the corner posts leading away from the edge of the tile when it is supported in position so as to reduce the contact of the tile with the corner post to a minimum. In Figure 7 flat tiles 18 are supported in position, it being understood, of course, that flat tiles may be supported in any of the other forms.

Due to its construction this device when loaded as a support unit will support considerably more flat tile than the old type of support. Therefore, considerably less space is required in the kiln for a given quantity of tiles. This does not necessitate an increase in heat units for the same number of tile so that the capacity of the kiln is materially increased in a given period of time.

Due to its interchangeable features, i. e., the fact that sets of posts of any desired length can be used with top and bottom plates of any width or length by merely substituting the desired dimensioned members to suit the need, the capital investment in "setters" for a tile manufacturing plant can be kept at a minimum, a complete set of all sizes not being necessary when changing from the manufacture of one size or shape of tile to another as the demand varies.

The cost of assembly is practically nil, and when assembled the "setter" can be used at once. This type of "setter" is held together by the force of gravity, and when once assembled it will stay together until more than one plate or post is cracked or broken. The old type of "setter", on the other hand, had to be carefully built up, piece by piece, and when assembled could not be used for firing ceramic ware until once fired empty to bond its component parts together.

Repair costs are reduced to a minimum. The old type "setter", if cracked or broken apart at any joint, or otherwise, had to be partly torn down and rebuilt of new material. Due to the fact that its component parts were bonded together in a single unit, this operation was difficult and invariably entailed the loss of many "layers" of the "setter" before it was broken apart successfully. In the new type "setter", if a part be broken or cracked it is only necessary to replace that particular part to complete the repair, and this can be done by the kiln man in a few seconds time.

Streaking of colored tile due to reflection of colors from cross-cleats and triangular plates of old type "setters", this color having been previously absorbed into cleats when "setter" was loaded with a different colored tile, is impossible with new type "setter" as it has no cross-cleats in its construction.

What I claim is:

1. A knock-down tile setter, including in combination a bottom member and a top member and a plurality of posts detachably mounted in said top and bottom members, said posts being provided with a plurality of lugs, the lugs of certain of said posts being arranged in opposed and parallel relation so as to support a ceramic product in a horizontal position, said lugs being spaced apart and the surfaces of said posts adjacent said lugs being inclined away from said lugs.

2. A knock-down tile setter device, including in combination a top member and a bottom member each provided with a plurality of sockets, a plurality of posts adapted to detachably fit in said sockets and connect said top and bottom members, each of said posts being provided with a plurality of supporting lugs, the lugs of certain posts being arranged in opposed and parallel relation to each other so as to support a ceramic product in a horizontal position, the surface of said posts adjacent to said lugs being inclined away from said lugs so as to space the posts from the side edges of the ceramic products supported thereby.

3. A knock-down tile setting device, comprising top and bottom members formed with enlarged portions adapted to space the bottom member as a whole from the support upon which it rests, said enlarged portions being provided with sockets, a plurality of

- posts having parts fitting in said sockets, whereby said top and bottom members and said posts may be assembled in a crate-like structure, said posts being provided with a plurality of laterally extending lugs having an inclined upper face, said lugs being adapted to support a ceramic product therebetween, said posts being provided with an inclined surface extending away from the upper face of each lug. 19
4. A knock-down tile setter all parts of which are interchangeable and composed of a baked bisque mixture, including top and bottom members similar in construction and each provided with a plurality of sockets, a plurality of posts similar in construction, the ends of each post fitting in one of said sockets to assemble the top and bottom members and the posts into a crate-like structure, each post being provided with a plurality of spaced lugs extending laterally from one face thereof, whereby when assembled a plurality of opposed parallel supporting lugs are provided to support a ceramic product in a horizontal position. 20
5. A knock-down tile setter all parts of which are interchangeable and composed of a baked bisque mixture, including top and bottom members alike in construction and each provided with a plurality of sockets, a plurality of posts alike in construction, the ends of each post fitting in one of said sockets to assemble the top and bottom members and the posts into a crate-like structure, each post being provided with a plurality of spaced lugs extending laterally from one face thereof, whereby when assembled a plurality of opposed parallel supporting lugs are provided to support a ceramic product in a horizontal position, the surfaces of said posts adjacent the top faces of said lugs being inclined away from said lugs to provide a space about the edges of the supported ceramic products. 25
6. A knock-down tile setting device comprising rectangular top and bottom members alike in construction and each provided with enlarged corners having sockets therein, a plurality of corner posts fitting within said sockets to assemble the parts into a crate-like structure, said corner posts each being provided with a plurality of spaced supporting lugs extending laterally from one face thereof and arranged in opposed relation to the lugs of the opposite post, whereby means is provided for supporting a ceramic product in a horizontal position. 30
7. A device of the character described including, in combination, a bottom member and a top member, and a plurality of posts detachably mounted in said top and bottom members, said posts being provided with a plurality of lugs, the lugs of certain of said posts being arranged in opposed and parallel relation so as to support a ceramic product in a horizontal position, said lugs compris- 35
- ing inclined members joined to said posts by inclined portions. 40
8. A device of the character described including, in combination, a bottom member and a top member, and a plurality of posts detachably mounted in said top and bottom members, said posts being provided with a plurality of lugs, the lugs of certain of said posts being arranged in opposed and parallel relation so as to support a ceramic product in a horizontal position, said lugs being spaced apart and comprising pointed angular members joined to said posts by inclined portions which are of substantially the same width as said lugs. 45
9. A device of the character described including, in combination, a bottom member and a top member, and a plurality of posts detachably mounted in said top and bottom members, said posts being provided with a plurality of lugs, the lugs of certain of said posts being arranged in opposed and parallel relation so as to support a ceramic product in a horizontal position, said lugs comprising inclined members joined to said posts by inclined portions and said lugs being separated and spaced by said inclined portions. 50
10. A knock-down tile setter including, in combination, a top member and a bottom member each provided with a plurality of sockets, a plurality of posts adapted to detachably fit in said sockets and connect said top and bottom members, each of said posts being provided with a plurality of supporting lugs, the lugs of certain posts being arranged in opposed and parallel relation to each other so as to support a ceramic product in a horizontal position, said lugs comprising inclined members joined to a short vertical portion of said posts by inclined portions. 55
- In testimony that I claim the foregoing, I have hereunto set my hand this 2nd day of August, 1929. 60
